UNITED STATES PATENT OFFICE.

WILLIAM H. CASSELL, OF WHEELING, WEST VIRGINIA.

DESIGN FOR A DRINKING VESSEL.

SPECIFICATION forming part of Design No. 33,458, dated October 30, 1900.

Application filed September 29, 1900. Serial No. 31,581. Term of patent 3¹ years.

To all whom it may concern:

Be it known that I, WILLIAM H. CASSELL, a citizen of the United States, residing at Wheeling, in the county of Ohio and State of West Virginia, have invented a new and original Design for Drinking-Glasses, of which the following is a specification.

My invention relates to a new and original design for a drinking-glass and is illustrated in the accompanying drawings, in which—

Figure 1 is a side elevation of the drinking-glass. Fig. 2 is a plan view looking into the bowl of the glass, and Fig. 3 is a sectional view on the line A B of Fig. 1.

15 The leading features of my design consist in a drinking-glass having a base, a stem rising therefrom, a bowl surmounting the stem, the exterior of which is circular throughout in horizontal section and which extends from 20 the stem in an upwardly-swelling convex body, is then contracted on concave lines to form a concave neck, above which is a convex shoulder and a flaring exteriorly-concave rim, and the interior of which is formed with 25 a series of separate horizontally-convex surfaces which, viewed from the outside of the glass, impart to the glass the appearance of having an angular exterior composed of a series of flat surfaces.

In the said drawings the reference-numeral 30 1 indicates the base. 2 is the stem rising therefrom, and 3 the bowl surmounting the stem. The exterior surface of the bowl is circular throughout in horizontal section, and, as shown, the bowl extends from the 35 stem in an upwardly-swelling convex body 4. It is then contracted on concave lines to form the concave neck 5, above which neck is formed a convex shoulder 6 and a flaring exteriorly-concave rim 7. The interior of the 40 bowl is formed with a series of separate horizontal convex surfaces 8, which when viewed from the outside of the glass impart to the latter the appearance of having an angular exterior composed of a series of flat surfaces. 45

Having thus described my invention, what I claim is—

The design for a drinking-glass, substantially as herein shown and described.

In testimony whereof I have hereunto set 50 my hand in presence of two subscribing witnesses.

WILLIAM H. CASSELL.
